(57) **CLAIM**

The ornamental design for a vehicle diagnosis tablet as shown and described.

DESCRIPTION

FIG. 1 is a first perspective view of a vehicle diagnosis tablet showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of encircled portion 9 of FIG. 2. The broken lines which depict portions of the vehicle diagnosis tablet form no part of the claimed design. The broken lines which represent boundaries of the enlarged views form no part of the claimed design.

1 Claim, 9 Drawing Sheets
